UNITED STATES PATENT OFFICE.

HENRY A. CARPENTER, ROBERT L. HIBBARD, AND CARLETON WARREN, OF SEWICKLEY, PENNSYLVANIA, ASSIGNORS TO RITER-CONLEY MANUFACTURING COMPANY, OF PITTSBURGH, PENNSYLVANIA, A CORPORATION OF NEW JERSEY.

CLOSURE MEANS FOR GAS-RETORTS.

1,145,672.

Specification of Letters Patent.

Patented July 6, 1915.

Application filed February 7, 1913. Serial No. 746,889.

To all whom it may concern:

Be it known that we, HENRY A. CARPENTER, ROBERT L. HIBBARD, and CARLETON WARREN, citizens of the United States, residing at Sewickley, in the county of Allegheny and State of Pennsylvania, have invented certain new and useful Improvements in Closure Means for Gas-Retorts, of which the following is a specification.

10 An object of our invention is to provide new and improved closure means for gas retorts.

A further object of the present invention is to provide improved door operating mechanism including means for maintaining the door in close contact with the front face of the mouth-piece of the retort, and means for effecting a sliding movement of the door on the mouth-piece to remove tar and other accumulations and thereby effect a gas-tight fit.

In the accompanying drawings, which illustrate an application of our invention: Figure 1 is a front elevational view of a retort closure means embodying our invention; Fig. 2 is a view showing in section a portion of a retort mouth-piece with our closure means in plan and applied thereto; Fig. 3 is a side elevational view particularly showing the latch mechanism; Fig. 4 is a part front view and a part vertical sectional view, the section being taken on line IV-IV of Fig. 2; Fig. 5 is a part side elevational view and a part sectional view, the section being taken on line V-V of Fig. 4 looking in the direction of the arrows; Fig. 6 is a horizontal sectional view taken on line VI-VI of Fig. 1; Fig. 7 is a plan showing the retort closure means partly open; and Fig. 8 is a detailed perspective view of an eccentric shaft employed.

Referring to the drawings, 1 designates an outer portion of a retort bench-wall, and 2 a retort mouth-piece applied thereto. Located at one side of the retort mouth-piece and projecting outwardly therefrom, are brackets 3, which support a hinge-pin 4. Extending transversely across the mouth-piece, we provide door carrying and door locking means comprising, as illustrated, two steel forgings or members 5 respectively formed with annular members 6 adapted to receive the ends of the hinge pin 4 and bearings therefor. In addition to the members

6, each member 5 is formed with a centrally disposed member 7, and each member 7 is 55 provided with an outwardly projecting bent arm 8. The free ends of the members 5 are brought together as clearly shown on the left of Fig. 1, and the opposite ends are separated and connected by a bolt 9. 60

10 indicates the door which is movable with and supported by members 5, the door being connected to said members by means of the arms 8 and tension springs 11, the latter connected to the bent extremities of 65 the arms and to lugs 12 formed integral with the door.

Located at the opposite side of the mouth-piece from the hinge pin 4 and supported therefrom by a projecting bracket 13 is a 70 latch mechanism comprising, as illustrated, a latch member proper 14 having apertured bent ends movable on parallel rods 15, the latter projecting from pin 16 formed integral with bracket 13. The outer ends of the 75 rods 15 are connected by a member 17, and interposed between the latter and latch member 14 are the rod embracing springs 18. When the door is in closed position the free ends of the locking members 5 are engaged by the spring-pressed latch member 14, as in full lines in Fig. 6, and the door is maintained tightly against the mouth-piece. 80

Designed to coöperate with the parts 85 above described and operable when opening and closing the door are means for relieving the pressure of springs 18 on members 5, and for effecting a lateral or sliding movement of the door on the face of the 90 mouth-piece. As illustrated, these means comprise an operating lever 19 carrying an eccentric shaft 20 with the ends thereof mounted in ball bearings 21 in the members 7. 95

22 designates the eccentric portion of the shaft 20, the latter being shown in detail in Fig. 8, the line *a—a* designates the center line of the shaft, and line *b—b* the center line of the eccentric portion thereof. 100

The eccentric shaft 20 projects through an annular casing 23 in which is disposed a ball bearing 24, the casing having trunnions 25 which bear in lugs 26 formed on the door. Supporting means is thus provided for the door in the nature of a uni- 105

versal joint, affording the door such movements relatively to the combined supporting and locking device as to cause the door to tightly engage all portions of the mouth-piece face under the pressure imparted through shaft 20. The door 10, as particularly shown by Fig. 5, is provided with recesses 27 into which project parts 7 of the door-carrying bars 5 when eccentric shaft 20 is turned by lever 19, as in dotted lines in Fig. 6, to permit said bars to respond to the pull of springs 11.

To open the door, lever 19 is thrown from the position shown in full lines in Fig. 6 to the position shown in dotted lines, thereby 15 rotating the eccentric shaft, and the resulting inward movement of bars 5 induced by springs 11 frees the extremities of the bars of pressure from latch springs 18. The latch 20 may then swing free of the door support, releasing the latter for outward or opening movement. After the door has been closed and the latch swung from the open position of Fig. 7 to that of Fig. 6, movement of lever 19 from the dotted to the full line position of Fig. 6 projects bars 5 away from the door, placing them under the holding and locking tension of latch springs 18.

In addition to movements of bars 5 relatively to the door made effective by shaft 20, the rotation of eccentric portion 22 of the latter in casing 23 results in lateral movement of the door relatively to the mouth-piece, clearing the face of the latter of tarry accumulation and causing the door 30 to close with a gas-tight fit.

In order to prevent the operating lever 19 from swinging violently toward open position under action of springs 11 after the 40 center line $b-b$ of shaft 20 is out of line with the center line $a-a$, we provide a spring 28 designed to retard the rotative movement of the eccentric shaft and its lever 19. This spring is secured to members 45, 5 by a yoke 29 and bolt 30, the spring being held forward under compression with its free end in contact with casing 23, and its rear end engaging a pin 31 carried by members 5. For maintaining the door 10 parallel with the face of the mouth-piece, we provide registering lugs 32 and 33, respectively carried by the door and the door carrying members 5.

What we claim is:

55 1. The combination of a retort door, a door locking device in front of the door with means for securing said device, springs connecting the door and said device and opposing movement of either of said parts away from the other, and means for effecting such movement in opposition to the springs.

60 2. The combination of a retort door, a door locking device in front of the door with means for securing said device, springs connecting the door and said device and oppos-

ing movement of either of said parts away from the other, and an eccentric mounted on the locking device and operating to move the latter away from the door in opposition to said springs when the door is closed.

70

3. The combination of a retort door, a door locking device in front of the door with means for locking said device, springs connecting the door and said device and opposing movement of either of said parts away from the other, an eccentric rotatably supported by the locking device, and a device mounted on the door and engaged by the eccentric for moving the locking device away from the door in opposition to said 75 springs when the door is closed.

80

4. The combination of a retort door, a combined supporting and locking device in front of the door, securing means for said device with said means having yielding 85 spring-opposed movement in the direction in which the door opens, a movable connection between the door and said combined device, and means for exerting closing pressure on the door and simultaneously moving the combined device in the direction in which the door opens and in opposition to its yielding securing means.

90

5. The combination of a retort door, a combined supporting and locking device in front of the door, a hinge support for one end of said device, a latch for the opposite end of said device, the latch having yielding 95 spring-opposed movement in the direction in which the door opens, a movable connection between the door and said combined device, and means for exerting closing pressure on the door and simultaneously moving the combined device in the direction in which the door opens and in opposition to its yielding latch.

100

6. The combination of a retort door, a combined supporting and locking device in front of the door, means for securing said device with said means having yielding 110 spring-opposed movement in the direction in which the door opens, an eccentric rotatably mounted on the combined device, and a bearing for the eccentric mounted on the door.

115

7. The combination of a retort door, a combined supporting and locking device in front of the door, securing means for said device, a movable door supporting connection between the door and said device for affording the latter movement relatively to the door, springs for opposing such relative movement, and means for imparting such relative movement to the support in opposition to said springs.

120

8. The combination of a retort door, a combined supporting and locking device in front of the door, securing means for said device, a movable connection between the door and the combined device, spring means 130

125

for opposing movement of said device away from the door, and a spring for opposing movement of said device toward the door in response to the force of the first mentioned 5 springs.

9. The combination of a retort door, a combined supporting and locking device in front of the door, a hinge support for one end of said device and a latch adapted to removably secure its opposite end, the latch having a movable part which engages said device and with springs on the latch for opposing movement of said part, a movable connection between the door and the combined device, and means for exerting closing pressure on the door and simultaneously moving the combined device in a direction to move said movable part of the latch in opposition to the latch-carried springs.
10. The combination of a retort door, a combined supporting and locking device in front of the door, a hinge support for one end of said device and a latch for removably securing its opposite end, the latch having a movable part engaged by said device and with springs on the latch for opposing movement of said part, a movement affording connection between the door and the combined device, springs connecting the door and said device and opposing movement of the latter away from the door, and means for moving the combined device away from the door in opposition to all of said 30 springs when the door is closed.

- 35 11. The combination with a retort mouth-piece, of a door therefor, a door carrying and locking member, a coöperating spring controlled latch, a spring connecting the door and the door carrying member, means

for effecting an inward and a lateral movement of the door carrying and locking member to release the latch and to move the door on the mouth-piece.

12. The combination with a retort mouth-piece, of a door therefor, door carrying and locking mechanism comprising a transversely extending member and a coöperating spring controlled latch, springs interposed between the door and the door carrying member, means for effecting an inward movement of the door carrying and locking member to release the latch including an eccentric shaft, means for rotating the shaft, and means for retarding the rotative movement of said eccentric shaft.

55 13. The combination with a retort mouth-piece, of a door therefor, a transversely extending door carrying and locking member, tension springs interposed between the door and the door carrying member for securing the door thereto, a spring controlled latch, means for moving the door carrying member toward the door and for effecting a sliding movement of the door on the mouth-piece comprising a casing having projections thereon in contact with engaging members formed on the door, an eccentric shaft extended through said casing, and a lever for rotating the eccentric shaft.

60 In testimony whereof we affix our signatures in presence of two witnesses.
